Primary Examiner — Selina Sikder*(74) Attorney, Agent, or Firm* — Chun-Ming Shih; HDLS IPR Services(57) **CLAIM**

The ornamental design for a heat sink, as shown and described.

DESCRIPTION

FIG. 1 is a perspective view of a heat sink showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is second perspective view thereof;

FIG. 9 is third perspective view thereof; and,

FIG. 10 is a perspective view showing the heat sink in use. The broken lines in the drawings illustrate portions of the heat sink that form no part of the claimed design.
